APPARATUS FOR COMPACTING POWDERS

Herman Jacob Glaxner, Monroe, La., assignor to
 Columbian Carbon Company, New York, N. Y.,
 a corporation of Delaware

Application July 8, 1932, Serial No. 621,419

8 Claims. (Cl. 100—35)

The invention relates to apparatus for compacting powders, and more particularly to an improved apparatus adapted for the treatment of extremely light and fluffy powders.

Certain powders, such as lamp black, carbon black and the like, when in loose state, are extremely fine, very light and fluffy and contain a great deal of occluded gas. When such powders are compressed while confined in a chamber, gas is retained in the powder and expands the powder back to or toward its loose, fluffy condition when the pressure is released. Furthermore, the powder so compressed has a tendency to scatter in dust-like fashion due to the escape or blowing out of the gas compressed therewith.

One object of the present invention is to provide an improved apparatus for compressing a powder in such a manner as to permit the escape of the contained or occluded gas during the application of pressure, whereby when the pressure is released the powder will retain its compact form.

As an important feature of the present invention, the apparatus provides for the continuous treatment of the powder, and includes two endless imperforate conveyer belts having a pair of surface facing converging straight runs between which the powder is compressed. The angle between these runs is very small to effect gradual compression of the powder, and the sides of the belts are open to permit the contained gas to escape.

As an added feature, the two belts at the apex of the converging runs pass over a single pulley, the powder being carried over the pulley between the belts where it forms a very thin compact layer. As this layer emerges from between the portions of the belts encircling the pulley, it is removed from one of the belts as flakes and conveyed to an outlet. The powder compressed by my improved apparatus will retain its compact shape after the pressure is released, and is not liable to scatter in dust-like fashion inasmuch as the greater part of the occluded gas or air has been ejected therefrom. The flakes formed by means of this apparatus may be further reduced and compressed into blocks by more powerful mechanical pressures. If desired, the powders may be subjected to a preliminary compression action before being treated in the apparatus of the present construction.

As a further feature of the present invention, the whole apparatus is enclosed in a dust-proof

casing, thereby preventing the escape of powder into the atmosphere.

In the accompanying drawing, there is shown for purposes of illustration, one form which the present invention may assume, and in which

Fig. 1 is a vertical section through a casing enclosing the press, and

Fig. 2 is a section taken on the line 2—2 of Fig. 1.

In the specific embodiment of the present invention there is provided a casing 10 which is substantially closed to render it dustproof, and in which is enclosed my improved belt press. This press includes an imperforate conveyer belt 11 passing over a pair of pulleys 12 and 13. A second or outer imperforate conveyer belt 14 is provided, and is so located with respect to the belt 11 as to form a pair of straight converging runs therewith between which the powder is adapted to be compressed. The belt 14 encircles the belt 11 and passes over a pulley 15 and the pulley 12, so that both belts pass over the latter pulley.

The lower run of the belts 11 and 14 are substantially straight, nearly horizontal and converge towards the pulley 12, as shown in Fig. 1, the angle between the two runs being very small. The pulley 15 is sufficiently large so that the upper runs of the belts diverge towards the right.

The shafts of the pulleys 12, 13 and 15 may extend beyond the sides of the casing 10 and are supported in suitable bearing blocks at the sides of the casing. The apertures in the casing through which these shafts extend are suitably covered by these blocks to prevent the escape of any substantial amount of powder therethrough. One or more of the shafts is driven by any suitable power means from the outside of the casing. Suitable means are provided for tightening the belts 11 and 14. For instance, the shafts of the pulleys 13 and 15 may pass through elongated apertures 16 in the sides of the casing 10, and are journaled in bearing blocks 17 on the outside of said casing 10. These bearing blocks 17 are mounted for slidable movement in guide yokes 18 fixed to the sides of the casing. Extending across one end of each yoke 18 is a crosspiece 19 supporting a screw 20 having one end thereof rotatably connected to the bearing block 17, while the other end is shaped to receive a suitable turning tool.

The powder to be compressed is fed into the interior of the casing 10 and upon the lower run of the belt 14 by suitable means, as for

instance a conveyer 22 having the receiving end outside the casing, and the discharge end mounted over the center of said belt 14. By means of this arrangement, the powder is dropped upon the center of the lower run of the belt 14 and is conveyed thereby towards the apex of the lower runs of the two belts. If desired, a spreader may be provided between the bottom runs of the belts, and advantageously takes the form of a bar 23 extending between the sides of the casing 10 and serving to level off the powder as it is carried by the belt 14.

As the powder travels to the left between the two converging runs of the belts, it is very gradually compressed, and the occluded gas or air is ejected therefrom and permitted to escape between the open sides of the belts. The linear speed of the belts should be very low so as to reduce the tendency of the powder to scatter over the sides of the belts during its compression. The belts are driven at the same linear speed or may be driven at different linear speeds, so as to subject the powder to a slight frictional, stroking action.

As the powder reaches the apex of the converging runs, it travels partway around the pulley 12 between the two belts, where it is subjected to a further pressure action, and where it forms a thin compressed layer. If desired, the powder may be subjected to a further pressure action by means of a freely rotatable roller 24 yieldably pressed against the belt 14 on the pulley 12. For that purpose, the roller 24 is mounted on a shaft 25 passing through elongated slots in the sides of the casing, and journaled in bearing blocks 27 which cover said slots. Each block is slidably mounted in a yoke 28 connected to the side of the casing, and is urged towards the pulley 12 by means of a spring 29 disposed between a crosspiece 30 and the bearing block 27. The pressure of the spring against the bearing block may be adjusted by means of a screw 31 passing through the crosspiece 30 and having a plate 32 engaging the end of the spring 29.

After the compressed powder has traveled around the pulley 12 between the two belts 11 and 14, it emerges at the top between the two upper runs of the belts. As the belt 14 leaves the circular pulley 12 it straightens out and causes any layer of powder which may have adhered to the under surface thereof to break off into flakes and fall upon the upper run of the belt 11. The belts 11 and 14 are advantageously made of rubber, and their facing surfaces between which the powder is compressed are made smooth to prevent the compressed powder from adhering too strongly thereto.

Adjoining the pulley 13 is a discharge conveyer 33 which receives the flakes leaving the belt 11 and conveys them to a point outside the casing 10. The flakes do not adhere to the outer surface of the belt 11 as said belt passes the pulley 13, since said belt in changing its curvature from a straight run to a circular run loosens the layer of compressed powder which may have adhered thereto. Any powder that falls off the sides of the conveyer 33 drops upon the lower run of the belt 14, and is reconveyed towards the converging runs of the two belts. Also, any powder that might adhere to the inside surface of the upper run of the belt 14 after passing to the right of the pulley 13 will fall upon the lower run of said belt and will be reconveyed towards the converging runs.

The powder being primarily along the center portion of the belt 14 causes a slight stretching of the center portion in passing around the pulley 12. Thus the edges of the two belts may come together and retard escape of the powder. The lower run of the belt 14 is also caused to assume a slightly trough-like form and thus aid in preventing the powder from falling off.

The casing 10 is not much wider than the width of the belts and the lower run of the belt 14 is spaced a short distance above the bottom of the casing. The powder which may fall off the sides of the lower run of the belt 14 piles up on the bottom of the casing and forms embankments alongside of the belt. These embankments serve to retain the powder on the belt.

Having thus described my invention, what I claim as new and desire to secure by Letters Patent is:—

1. An apparatus for compressing light, dry, fine, fluffy powder, including a pair of spaced pulleys, having parallel axes disposed in a substantially horizontal plane, an endless imperforate conveyer belt tightly passing around said pair of pulleys and presenting substantially horizontal upper and lower runs, a third pulley disposed between said runs, and having its axis parallel to the axes of said first mentioned pulleys, said third pulley being spaced from said runs and having a diameter less than the distance between said runs in the vertical plane of the axis of said third pulley, a second imperforate conveyer belt passing tightly around said third pulley and one of said pair of pulleys, 30 encircled by said first mentioned belt, and presenting upper and lower runs, the pair of upper and the pair of lower runs converging to the periphery of said last mentioned pulley, and means for delivering the powder to be compressed onto the lower run of one of said pairs, said third pulley being sufficiently close to one of the runs of said first mentioned belt so that the angle between the latter run and the adjacent run of the second mentioned belt is very small, whereby gas above said powder and gas occluded within said powder may escape at a sufficiently low velocity so as not to disturb the layer of powder as the latter is advanced to one of said pair of pulleys.

2. An apparatus for compressing light, dry, fine, fluffy powder, including a pair of spaced pulleys having parallel axes disposed in a substantially horizontal plane, an endless imperforate conveyer belt tightly passing around said pair of pulleys, and presenting substantially horizontal upper and lower runs, a third pulley disposed between said runs, and having its axis parallel to the axes of said first mentioned pulleys, said third pulley being spaced from said runs, and having a diameter less than the distance between said runs in the vertical plane of the axis of said third pulley, a second imperforate conveyer belt passing tightly around said third pulley and one of said pair of pulleys, 60 encircled by said first mentioned belt, and presenting upper and lower runs, the pair of upper and the pair of lower runs converging to the periphery of said last mentioned pulley, means for delivering the power to be compressed onto the lower run of one of said pairs, said third pulley being sufficiently close to one of the runs of said first mentioned belt so that the angle between the latter run and the adjacent run of the second mentioned belt is very small, 70 whereby gas above said powder and gas occluded within said powder may escape at a sufficiently low velocity so as not to disturb the layer of powder as the latter is advanced to one of said pair of pulleys.

5 whereby gas above said powder and gas oc-
cluded within said powder may escape at a
sufficiently low velocity so as not to disturb the
layer of powder as the latter is advanced to
one of said pair of pulleys, and a casing enclosing
said belts and pulleys and substantially closed
to prevent escape therefrom of powder
floating in the air in said casing.

10 3. An apparatus for compressing powder, in-
cluding a pulley having a horizontal axis, a
pair of endless imperforate conveyer belts passing
around said pulley in superposed relation-
ship, means horizontally spaced from said pulley
in a direction at right angles to the axis thereof
15 for supporting the inner belt, and of approxi-
mately the height of said pulley, means hori-
zontally spaced from said pulley in the same
direction, and extending above and below said
first mentioned means, for supporting the outer
20 belt, whereby the upper and lower runs of both
belts are in superposed relationship, correspond-
ing runs being spaced apart and converging to
said pulley and the angle between one pair of
corresponding runs being very small to effect
25 gradual compression of the powder therebe-
tween, and the slow escape of occluded gas from
said powder, and means for delivering the pow-
der between the two runs of said latter pair.

30 4. An apparatus for compressing powder, in-
cluding a pulley having a horizontal axis, a pair
of endless imperforate conveyer belts passing
around said pulley in superposed relation-
ship, means horizontally spaced from said pulley
35 in a direction at right angles to the axis thereof
for supporting the inner belt, and of approxi-
mately the height of said pulley, means hori-
zontally spaced from said pulley in the same direc-
tion, and extending above and below said first
40 mentioned means for supporting the outer belt,
whereby the upper and lower runs of both belts
are in superposed relationship, correspond-
ing runs being spaced apart and converging to said
pulley, and the angle between one pair of corre-
45 sponding runs being very small to effect gradual
compression of the powder therebetween and the
escape of air at low velocity from above said
powder, means for delivering the powder be-
tween the two runs of said latter pair, a casing
50 enclosing said pulley, belts and supporting
means, and means adjacent to said first men-
tioned means for removing the compacted pow-
der from said casing.

55 5. An apparatus for compressing powder, in-
cluding a pulley having the axis thereof substan-
tially horizontal, an endless imperforate con-
veyer belt passing over said pulley, and sup-
ported by said pulley, means spaced from said
60 pulley for supporting the belt and for tightly
extending the portions of the belt substantially
horizontally between said belt and said means,
a second imperforate conveyer belt encircling
said first mentioned belt and passing over said
pulley, and means horizontally spaced to a
65 greater distance from said pulley for supporting
said second belt and for tightly extending the
runs of the latter belt adjacent to the runs of
the first belt, the juxtaposed runs being approxi-
mately horizontal and converging at a small
70 angle towards said pulley, whereby the air above
said powder escapes at low velocity.

6. An apparatus for compressing light, fine,
fluffy powder, including a pair of endless im-

5 perforate conveyer belts, one of said belts being
substantially longer than the other, a pulley
around which said belts extend in direct super-
posed relationship, means spaced from said pulley
for supporting said belts in encircling re-
lationship and for tightly extending said belts
in directions to form a pair of substantially hori-
zontal superposed spaced runs converging at a
small angle to said pulley and permit escape of
air at low velocity as said powder approaches
10 said pulley and adapted to receive powder there-
between and compress it as said belts travel to-
ward and around said pulley, a casing enclosing
said belts and substantially closed to prevent
15 escape of any substantial amount of dust there-
from, and having an opening in one wall there-
of, and a conveyer passing through said opening,
and having the receiving end thereof outside the
casing and the discharge end between the con-
verging horizontal runs of said imperforate belts. 20

7. An apparatus for compressing light, fine,
fluffy, dry powder, including a pair of spaced
pulleys having parallel axes disposed in a sub-
stantially horizontal plane, an endless imper-
forate conveyer belt passing around said pair 25
of pulleys and presenting substantially horizon-
tal upper and lower runs, a third pulley disposed
between said runs and having its axis parallel
to the axes of said first mentioned pulleys, said
third pulley being spaced from said runs, and 30
having a diameter less than the distance between
said runs in the vertical plane of the axis of said
third pulley, a second imperforate conveyer belt
tightly passing around said third pulley and one
of said pair of pulleys, encircled by said first 35
mentioned pulley, and presenting upper and
lower runs, the pair of upper and the pair of
lower runs converging to the periphery of said
last mentioned pulley, said third pulley being
sufficiently close to one of the runs of said first 40
mentioned belt so that the angle between the
latter run and the corresponding run of the
second mentioned belt is very small, and means
for independently moving said third pulley and
the other one of said pair of pulleys in a substan- 45
tially horizontal direction, whereby the belts
may be independently tightened without chang-
ing the angle between corresponding runs.

8. An apparatus for compressing light, fine,
dry, fluffy powder, including a pulley having a 50
horizontal axis, a pair of endless imperforate
conveyer belts passing around said pulley in su-
perposed relationship, means horizontally spaced
from said pulley in a direction at right angles
to the axis thereof for supporting the inner 55
belt, means horizontally spaced from said pulley
in the same direction, and extending above and
below said first mentioned means, for supporting
the outer belt, whereby the upper and lower
runs of both belts are in superposed relationship, 60
corresponding runs being spaced apart and con-
verging to said pulley, means for delivering the
powder to be compressed onto the lower of said
converging runs, the angle between one pair of
said corresponding runs being very small to effect 65
the removal of gas from above and within said
powder at low velocity and the gradual com-
pression of said powder and means for tighten-
ing said belts independently of each other with-
out changing the angle between corresponding 70
runs of said belts.

HERMAN JACOB GLAXNER.
